HOLDER FOR A HEARING AID INSTRUMENT

Simon Relman, Forest Hills, N. Y.

Application December 21, 1955, Serial No. 39,410

Term of patent 3½ years

(Cl. D26—14)

Figure 1 is a perspective view of a holder for a hearing aid instrument, showing my new design;

Figure 2 is a front view thereof;

Figure 3 is a rear elevational view thereof with a portion of the upper and lower straps omitted for convenience of illustration; and

Figure 4 is a side elevational view thereof with a portion of the upper and lower straps omitted for convenience of illustration.

I claim:

The ornamental design for a holder for a hearing aid instrument, as shown.
